UNITED STATES PATENT OFFICE.

MARY A. LOYER, OF DENVER, COLORADO.

MEANS FOR CHARGING WATER WITH RADIO-ACTIVITY.

1,208,806.

Specification of Letters Patent. Patented Dec. 19, 1916.

Application filed September 23, 1915. Serial No. 52,274.

To all whom it may concern:

Be it known that I, MARY A. LOYER, a citizen of the United States, and a resident of the city and county of Denver, State of Colorado, have invented certain new and useful Improvements in Means for Charging Water with Radio-Activity, of which the following is a full, clear, and exact description, such as will enable others skilled in the art to which the invention appertains to make and use the same, reference being had to the accompanying drawing, forming a part hereof.

The invention relates to improvements in receptacles adapted to contain a quantity of carnotite ore exposed to the circulation of water through said receptacle, whereby the water is charged with the radium therapeutic qualities.

Another object of the invention is to provide a receptacle of the class specified which may be conveniently attached to a water faucet, causing the water to pass through said receptacle and take up therapeutic qualities of radium, or other material adapted to be retained in said receptacle.

With these and other objects in view, the invention will now be described with reference to the accompanying drawing.

In this drawing, Figure 1 is a longitudinal sectional view of the receptacle; and Fig. 2 is a cross sectional view of the same, taken on the line 2—2, Fig. 1.

Corresponding and like parts are referred to in the following description and indicated in all the views of the accompanying drawing by the same reference characters.

Let the numeral 5 designate the upper part of the receptacle, the same being formed of a solid wall, and having a cap 6 threaded on the top thereof, as shown at 7.

The numeral 8 designates the lower part of the receptacle, which is attached to the lower extremity of the upper part 5 of the receptacle. This lower part 8 is composed of an upper ring 9 and a lower ring 10, the two rings being connected by vertical stays 12, the said stays holding the rings in spaced apart relation and forming a frame, on the interior of which, vertically disposed

screens 13 and 14 are arranged. These screens 13 and 14 are spaced apart by means of upper and lower spacing rings 15 and 16. The upper ring 9 is threaded on a part 17, which is integrally formed with the lower extremity of the part 5 of the housing, the part 17 being of less diameter than the part 5 of the receptacle, whereby a shoulder 18 is formed against which the ring 9 is set. A cap 19 is threaded into the ring 10, the said cap being provided with an inwardly set flange 20, on which the threads are provided. The cap 19 is provided with a shoulder 21 by means of which the said cap may be operated. An annular collar 20 rests on the flange 21 and supports the screens 13 and 14 as well as to serve as a spacing member for an inner housing 22. The carnotite ore, or other material is placed in this inner housing 22, the latter being formed of sheet iron, or other substantial and stable material, and having its wall perforated to permit the water to pass therethrough. The upper edge of the housing 22 is provided with a horizontally disposed outwardly extending flange 23, the said flange being cut out, as shown at 24 to form a seat for a screen 25, which covers the top of said housing 22. The inner side of the wall of the part 5 of the receptacle, near the lower extremity of said part, is provided with an annular horizontally disposed flange 26, a gasket 27 being interposed between this flange 26 and the flange 23, thereby forming a water-tight engagement of the housing 22 with said flange 26 and causing the water to pass through the housing 22 instead of escaping from the part 5 to the exterior of the housing 22. The bottom of the housing 22 rests on the cap 19, and by adjusting the cap 19, the flange 23 of the housing 22 is caused to firmly engage with the flange 26. An annular space is left between the housing 22 and the screen 14, into which, the water enters after passing through the housing 22. The vertical members 12 serve to protect the screens 13 and 14 against injury, the said members being separated from the outer screen 13.

The device is attached to the water faucet in any desired or convenient manner. In the drawing, I have provided the cap 6 with a sleeve 28, which communicates with the 5 interior of the part 5 of the housing, the said sleeve being provided with interior threads adapted to engage with threads provided on the water faucet 29. In many cases, faucets are not provided with threads, 10 and in such instances, the device may be attached and held in position to the faucet by means of a bail 30, fulcrumed on the cap 6, as shown at 31. This bail is adapted to be looped over the faucet as shown in dotted 15 lines, the mouth of the faucet being received in the sleeve 28. The bail 30 is formed of pliable spring wire, whereby the same may be twisted or crimped where necessary to properly adjust the bail to the faucet in 20 such manner as to sustain the device in a proper position with respect to the faucet.

In operation, the water passes from the part 5 of the receptacle through the screen 25, the latter retaining any foreign substances, into the housing 22, wherein the water comes into contact with the carnitite ore, being charged with radio-activity by said ore. The water passes through the perforations of the housing 22 and through the 30 screens 13 and 14 into the basin. Thus, by this device, water is charged with radio-activity and used for its therapeutic qualities, either for drinking or bathing purposes.

While I have described and illustrated 35 herein, a specific form of the invention, it is understood that I am not limited thereto and that the invention may be modified and varied, according to the particular conditions under which it is being used and to suit 40 convenience and taste, without departing from the spirit of the invention or the scope of the appended claims.

Having thus described the invention, what 45 I claim and desire to secure by Letters Patent is:

1. A device of the class described, comprising a receptacle, said receptacle consisting of upper and lower parts, the lower part comprising a frame detachably secured to 50 the upper part, a vertically disposed screen retained by said frame, a perforated housing retained in position by said frame and encircled by said screen, and the upper part of said receptacle having an interior member therein with which the upper part of 55 said perforated housing is engaged.

2. A device of the class described, comprising a receptacle, said receptacle consisting of upper and lower parts, the lower part 60 comprising a frame detachably secured to said upper part, a screen retained by said frame, an annular flange disposed on the interior of the upper part of said receptacle, a housing retained in position by said frame

and surrounded by said screen, the upper 65 extremity of said housing engaging with said flange, and means for securing the upper part of said receptacle to a water faucet.

3. A device for charging water with therapeutic qualities, consisting of a receptacle composed of two parts detachably connected together, one of said parts comprising two rings spaced apart, stays connecting said rings and holding the latter in their spaced apart relation, one of said rings 75 adapted to be engaged with the other part of said receptacle, a cap threaded in the other ring, a screen held in position by said rings, and a perforated housing seated on said cap and encircled by said screen. 80

4. A device for charging water with therapeutic properties, comprising a receptacle composed of upper and lower parts, one of said parts comprising two rings spaced apart, stays connecting said rings, 85 the lower extremity of the upper part of said receptacle having a member thereon, one of said rings adapted to be threaded on said member, a cap threaded in the other ring, a screen held in position by said rings, 90 a housing seated on said cap and encircled by said screen, the upper extremity of said housing having a horizontally disposed outwardly extending flange, the interior of the upper part of said receptacle having an 95 annular flange engaged by said flange of said housing, and a screen covering the top of said housing and engaged between said flanges, the said flange of said housing having a portion cut out to receive the edge of 100 said last named screen.

5. A device for charging water with therapeutic qualities, consisting of a receptacle composed of upper and lower parts, the wall of the upper part being solid, the lower 105 part consisting of a frame, said frame being composed of two rings spaced apart, stays connecting said rings and holding the latter in their spaced apart relation, one of said rings being threaded on the lower extremity 110 of the upper part of said receptacle, a cap threaded in the other ring and forming the bottom of the lower part of said receptacle, vertically disposed screens held in position by said frame, a housing seated on said cap 115 and encircled by said screens, a spacing ring held by said frame and encircling said housing near the lower part of the latter, the upper extremity of said housing having an outwardly extending flange, the interior of 120 the upper part of said receptacle having an annular flange engaged by the flange of said housing, the wall of said housing being perforated, and means for securing said receptacle to a water faucet. 125

6. A device of the class described, comprising a receptacle consisting of an upper and a lower part, the lower part comprising

a frame detachably secured to the upper part, a perforated housing retained in position by said frame in communication with the upper part of said receptacle, the upper 5 edge of said perforated housing having an outwardly extending flange, and the interior of said upper part of said receptacle having an inwardly extending flange adapted to be

engaged by the flange of said perforated housing.

In testimony whereof, I affix my signature in the presence of two witnesses.

MARY A. LOYER.
